UNITED STATES PATENT OFFICE.

ELLSWORTH E. FLORA, OF CHICAGO, ILLINOIS.

MACHINE FOR SAWING STAVES.

No. 832,602.

Specification of Letters Patent.

Patented Oct. 9, 1906.

Application filed June 12, 1905. Serial No. 264,928.

To all whom it may concern:

Be it known that I, ELLSWORTH E. FLORA, a citizen of the United States of America, and a resident of Chicago, Cook county, Illinois, have invented a certain new and useful Improvement in Machines for Sawing Staves, of which the following is a specification.

My invention relates to an automatic stave-sawing machine.

10 The object of my invention is to provide a machine for the sawing of staves for barrels, kegs, tubs, or other receptacles in which it is necessary to use rounded segmental parts for forming their periphery.

15 More particularly, the object of my invention is to provide a machine of which each operation is strictly automatic and when once started will continue to operate and adjust the bolt or billet after one stave has been 20 removed therefrom into position for the cutting of the next stave.

The particular objects of my invention are to provide a stave-sawing machine with a carriage for carrying the bolt or billet which 25 is automatically shifted backward and forward; to provide means for automatically varying the speed of the advance movement of said carriage, whereby the rate at which the billet is fed into the saw may be controlled by the hardness of the wood or the 30 difficulty of cutting it; to provide means for adjusting the backward and forward movement of said carriage, so that its movement may be controlled manually; to provide 35 means for automatically releasing the bolt or billet upon the return of the carriage to its initial position and means for clamping said billet and holding it firmly upon the carriage at the moment said carriage begins its forward movement; to provide a stave-sawing 40 machine in which a stave when nearly cut through from the under side of the billet will be supported so that it will not split off or leave a stub-short—in other words, will permit the saw to cut through to the end of the 45 billet, leaving the stave free from any irregularity throughout its entire length; to provide a stave-sawing machine in which the table is automatically adjusted so as to be 50 adapted to receive billets of irregular shape in such a position that the saw will run parallel with the grain of such irregular billets; to provide a stave-sawing machine with adjustable and pivotal locking clamps for holding the bolt or billet to the carriage, so that 55 irregularities in the end cut of the billet will

not interfere with the secure clamping of said bolt or billet. These and other objects of my invention will hereinafter more fully appear.

60 In the accompanying drawings, Figure 1 is a side view of my improved stave-sawing machine. Fig. 2 is a plan view of said machine. Fig. 3 is a side view opposite Fig. 1. Fig. 4 is an end view. Fig. 5 is a vertical 65 longitudinal sectional view on the line 5 5 of Fig. 4. Figs. 6 to 9, inclusive, are detail views.

A represents the frame of my improved automatic stave-sawing machine, in which is mounted upon suitable bearings B a driving-shaft C, provided with a driving-pulley D, together with a counter-pulley E. Upon the driving-shaft C is mounted the cylindrical saw F, adapted to rotate and to cut from the under side of the billet the stave to be 70 sawed as the carriage G is advanced toward the saw. The carriage G consists of two cross-heads connected together by parallel rods or bars q⁷ and q⁸. Each cross-head is provided with supporting-rollers q²⁰ and 75 guide-rollers q²¹ to facilitate the movement of the carriage back and forth upon suitable rails q²², mounted upon the side frames of the machine.

80 The movement of the carriage G is controlled by friction-disks H and H', which are automatically brought in contact with another disk I, which is driven by worm-gearing and the counter-shaft J, upon which is mounted the counter-pulley K, which is 85 adapted to be suitably connected with the counter-pulley E, mounted upon the driving-shaft C. The friction-disk H is slidably mounted or splined on the shaft L, which in turn is mounted in suitable bearings l and l', 90 attached to the frame A. Rigidly mounted upon the shaft L is a gear-wheel M, and meshed with this gear-wheel and mounted upon the shaft N is the gear-wheel O. The shaft N is also mounted in suitable bearings 95 n and n', rigidly attached to the frame A. Upon the shaft N is also rigidly mounted the friction-disk H' in such a position that it will engage the face of the friction-disk I opposite to that face engaged by the friction-disk H and at such a distance from the friction-disk H that when the friction-disk H is in engagement with the face of the friction-disk I the friction-disk H' will be out of engagement with the opposite face of the friction-disk I. 100 The friction-disk H is provided with a hub h, in which is cut an annular groove, and in the 105 110

groove is inserted a collar h^2 , having trunnions h^{20} , to which is attached a rocking arm h^3 , rigidly mounted upon the rock-shaft h^4 . The rock-shaft h^4 is suitably mounted in bearings h^5 and h^6 upon the frame A. At the opposite end of the shaft h^4 and rigidly attached thereto is the lever h^7 . By means of this lever h^7 the friction-disk H can be adjusted manually with respect to the friction-disk I, and by this means the speed of the gear-wheel M may be varied, thus varying the speed of the gear-wheel O and through it the speed of the gear-wheel P, which is also rigidly mounted upon the shaft N. The gear-wheel P engages a rack R', rigidly attached to the carriage G, and provides a means for shifting the carriage backward and forward. Thus by adjusting the lever h^7 the rate of the advance movement of the carriage G may be manually controlled. Rigidly attached to the friction-disk I is the worm gear-wheel T, which meshes into and is driven by the worm S, rigidly fixed upon the counter-shaft J, thus forming a complete power-transmitting connection between the driving-shaft C and the carriage G. It will thus be seen that if in the act of sawing the stave the saw strikes a knot or any obstruction in the billet, causing the speed of the saw to slacken, the advance movement of the carriage will slacken proportionately. Thus the feed is automatically controlled.

For automatically reversing the direction of the movement of the carriage G the friction-disk I is revolvably mounted upon the shaft i, which in turn is suitably mounted in bearings in the frame A, so that the shaft i can be longitudinally shifted in the bearings in the frame A. Upon the shaft i and rigidly attached thereto is the collar i', forming a stop for the spring i², which has for its seat the frame A. Upon the shaft i and rigidly attached thereto is also the collar i³, which is provided with an upwardly-extending arm i⁴, which in turn is adapted to be engaged by the stops q and q', attached to the framework of the carriage G. These shiftable stops q and q' may be adjusted by the set-screws q³ and q⁴ to any desired position relative to the framework of the carriage G. The collar i³ is provided with a cam-surface i⁵, which in turn slides upon a cam-surface i⁶ of a cam i⁷, rigidly attached to the frame A. Thus by the movement of the upwardly-extending arm i⁴, caused by the engagement with the stops q and q', the shaft i is rocked. The cam-surface i⁵ of the cam i⁷ slides upon the cam-surface i⁶ of the rigid cam i⁷, thereby shifting longitudinally the shaft i, compressing the spring i², and shifting the friction-disk I out of engagement with the friction-disk H' and into engagement with the friction-disk H. By this means the friction-disk H is operated, thus reversing the movement of the gear-wheel P, and thus reversing the move-

ment of the carriage G. The cam-surfaces i⁵ and i⁶ will remain in this shifted position until in the backward movement of the carriage G the stop q engages the shifting-lever i⁴ and restores the two cams to their normal position and then through the action of the spring i² shifting the friction-disk I into engagement with the friction-disk H'. Provision is made for rocking shaft i manually by securing at one end thereof a handle i⁸.

For holding the bolt or billet in place while being sawed I provide serrated clamping-jaws q⁵ and q⁶. The serrated clamping-jaw q⁵ is slidably mounted upon the rods q⁷ and q⁸ of the carriage G, and attached to the serrated jaw q⁵ are toggle connections q⁹ and q¹⁰, which are bound together by a spring q¹¹, always under tension. The toggle connections q⁹ and q¹⁰ are pivotally connected to other toggles q¹² and q¹³, which are pivoted to the cross-head q¹⁴ of the carriage G. The toggles q¹² and q¹³ are provided with outer arms q¹⁵ and q¹⁶, which in the backward movement of the carriage G meet with stops a and a', rigidly attached to the frame A. By this means the serrated jaw q⁵ is withdrawn from its hold upon the bolt or billet and the bolt or billet is allowed to fall upon a table U. Immediately upon the advance of the carriage G the arms q¹⁵ and q¹⁶ are released from their engagement with the stops a and a', and through the action of the spring q¹¹ the serrated jaw q⁵ is advanced along the rods q⁷ and q⁸ and engages and holds firmly in place the bolt or billet. The serrated jaw q⁶ is also slidably mounted upon the rods q⁷ and q⁸ and is provided with a screw and hand-wheel adjustment q¹⁷ for the purpose of adjusting the jaw to the different lengths of the bolt or billet to be sawed.

For adjusting the position of the bolt or billet within the serrated jaws q⁵ and q⁶, so that the stave to be sawed may be sawed straight with the grain of the bolt or billet and to regulate the thickness of the stave, I provide a tilting table U, hinged to the frame V at u and supported by a lug u', which rests upon an adjusting device u², also pivoted to frame V. Frame V is vertically adjustable with respect to the frame A in suitable guide-ways attached to the frame by means of a screw R, provided at its lower end with a bevel-gear r, engaging the bevel-gear r', rigidly attached to the shaft r², and the hand-wheel r³. Any other of the many well-known devices may be substituted for the screw R for accomplishing this adjustment without departing from the spirit of my invention. By means of this adjusting-screw R the subsidiary frame V and the table U, attached thereto, can be raised or lowered, thus regulating the position of the bolt or billet when the clamping-jaw q⁵ impinges upon the forward end of the bolt or billet, and thus regulating the distance the bolt or billet is held

below the carriage G and providing a means for controlling the thickness of the stave to be sawed.

For adjusting the table with reference to the grain of the billet to be sawed an adjusting device is provided consisting of a toothed segment u^2 , pivoted at u^3 to the frame V and having a cam-surface upon its upper edge which contacts with the lug u' upon one end 10 of the table. This segment is also provided with an extended arm, to the end of which is attached a spring u^5 , the other end of the spring being connected to the main frame. To operate the segment, a rod u^4 , connected thereto and to a foot-lever, is provided, and to hold said segment in its normal and adjusted positions a gravity-pawl u^7 is provided, being pivoted to the frame V and having an upwardly-extending arm. Said pawl 15 is operated by a stop q^{19} , secured to the frame of the carriage G. When the carriage reaches the limit of stroke toward the saw, this operation returns the table to its normal position to receive the billet ready to be adjusted again 20 as desired. The sides of the main frame are connected together by the cross-braces and supports A^3 A^4 , and rigidly mounted upon these cross-braces are the side supports a^3 a^4 of the conveyer X, which extends into the 25 saw F.

Mounted upon the side support a^3 within the saw F is the rock-shaft W, to which the rock-arms w and w' are rigidly attached. These arms are so arranged within the saw 30 that they will form a support for the stave when the kerf of the saw is nearly cut through, thus preventing the stave from falling down before it is completely cut off and preventing a stub-short from remaining upon 35 the end of the staves. The rock-shaft W is revolvably mounted in bearings w^3 , attached to the side support a^3 . The said rock-shaft W is provided at that end which projects from the saw with a spiral or twisted cam-surface against which a lug q^{18} presses when 40 the carriage G is nearing the completion of its advance movement, thereby causing the rock-bar W to rotate and the arms w and w' to swing up and support the stave until cut off, 45 the said arms remaining in this position until the carriage G returns sufficiently to release the spiral cam w^4 from the pressure of the lug q^{18} . The stave then falls of its own weight upon an endless-belt conveyer X, which is 50 adapted to run upon rollers between the side supports a^3 and a^4 .

The operation is as follows: A billet of wood to be sawed is placed upon the table U, and the table is then adjusted to the grain of 55 the wood and also in relation to the thickness of the stave to be sawed. Power is then applied, the carriage starts to move forward, and at the start the toggle-levers are released from their stops, causing the serrated carrying-jaws to bite into the billet and carry

it forward to the saw. When the stave has almost been sawed from the billet, the lug q^{18} upon the carriage contacts with the spiral cam w^4 , turning the rock-shaft W and elevating the arms w and w' to support the stave 70 until it is completely sawed from the billet, preventing any stub-short. At the beginning of the return of the carriage the lug q^{18} gradually allows the spiral and rock-shaft to turn, causing the supporting-arms to drop, 75 allowing the stave to fall directly upon the conveyer X and be carried to the end of the machine. The billet is then carried back and deposited again upon the table.

I claim—

1. A machine for sawing staves comprising a frame, a main driving-shaft, a cylindrical saw, a carriage for carrying the bolt or billet to the saw, means for imparting movement to said carriage and a pivoted stave-support 85 within the saw operated by the carriage.

2. A machine for sawing staves, comprising a frame, a main driving-shaft, a cylindrical saw, a table for supporting a billet to be sawed, a carriage for carrying the billet to 90 the saw, means for imparting movement to said carriage and a pivoted stave-support within the saw operated by the carriage.

3. A machine for sawing staves, comprising a frame, a main driving-shaft, a cylindrical 95 saw, a table for supporting a billet to be sawed, a carriage for carrying the billet to the saw, means for imparting a back-and-forth movement to the carriage and a pivoted stave-support within the saw operated by 100 the carriage.

4. A machine for sawing staves, comprising a frame, a main driving-shaft, a cylindrical saw, a table for supporting a billet to be sawed, a carriage for carrying the billet to 105 the saw, means for imparting a back-and-forth movement to the carriage, and a pivoted stave-support and means for operating the pivoted support to a position to support the stave during the forward movement of 110 the carriage and to a discharging position during the backward movement of the carriage.

5. A machine for sawing staves, comprising a frame, a main driving-shaft, a cylindrical 115 saw, table for supporting a billet to be sawed, a carriage for carrying the billet to the saw, means for imparting a back-and-forth movement to the carriage, a pivoted stave-support and means for operating the pivoted support to a position to support the stave during the forward movement of the carriage and to a discharging position during the backward movement of the carriage, and a conveyer.

6. A machine for sawing staves, comprising a frame, a main driving-shaft, a cylindrical saw, a table for supporting a billet to be sawed, a carriage for carrying the billet to 130 the saw, means for imparting a back-and-

forth movement to the carriage, a pivoted stave-support within the saw and means for operating the pivoted support to a position to support the stave during the forward movement of the carriage and to a discharging position during the backward movement of the carriage, and a conveyer.

7. A machine for sawing staves, comprising a frame, a main driving-shaft, a cylindrical saw, a table for supporting a billet to be sawed, a carriage for carrying the billet to the saw, means for imparting a back-and-forth movement to the carriage, a pivoted stave-support comprising a rock-shaft, suitable supports therefor, supporting-arms projecting from the rock-shaft and a cam upon the shaft, and a conveyer.

8. A machine for sawing staves, comprising a frame, a main driving-shaft, a cylindrical saw, an adjustable table for supporting a billet to be sawed, a carriage for carrying the billet to the saw, means for imparting a back-and-forth movement to the carriage, a pivoted stave-support within the saw and a conveyer.

9. A machine for sawing staves, comprising a frame, a main driving-shaft, a cylindrical saw, an adjustable table for supporting a billet to be sawed, means for adjusting said table vertically, means for adjusting said table angularly, a carriage for carrying the billet to the saw, means for imparting a back-and-forth movement to the carriage, a pivoted stave-support within the saw, and a conveyer.

10. A machine for sawing staves, comprising a frame, a main driving-shaft, a cylindrical saw, an adjustable table for supporting a billet to be sawed comprising a support for the billet mounted upon a suitable frame said frame adapted to slide in suitable guideways upon the main frame and means for adjusting a carriage for carrying the billet to the saw, means for imparting a back-and-forth movement to the carriage, a pivoted stave-support within the saw and a conveyer.

11. A machine for sawing staves, comprising a frame, a main driving-shaft, a cylindrical saw, a vertically and angularly adjustable table for supporting a billet to be sawed comprising a support for the billet pivotally mounted upon a suitable frame, said frame adapted to slide in suitable guideways upon the main frame, means for adjusting vertically and means upon the vertically-adjustable frame for angularly adjusting the supporting-table, a carriage for carrying the billet to the saw, means for imparting a back-and-forth movement to the carriage, a pivoted stave-support within the saw, and a conveyer.

12. A machine for sawing staves, comprising a frame, a main driving-shaft, a cylindrical saw, a vertically and radially adjustable table for supporting a billet to be sawed, comprising a support for the billet pivotally mounted upon a suitable frame, said frame

being vertically adjustable, means for adjusting it vertically and means upon the said vertically-adjustable frame for radially adjusting the table comprising a spring-held pivoted toothed segment supporting one end of the table, means for operating the segment and means for retaining it in its adjusted position, a carriage for carrying the billet to the saw, means for imparting a back-and-forth movement to the carriage, a pivoted stave-support and a conveyer.

13. A machine for sawing staves, comprising a frame, a main driving-shaft, a cylindrical saw, a vertically and angularly adjustable table for supporting a billet to be sawed, a carriage for carrying the billet to the saw, comprising a suitable frame supporting clamping-jaws automatically operated to clamp and release the billet, means for imparting a back-and-forth movement to the carriage, a pivoted stave-support mounted within the saw, and a conveyer.

14. A machine for sawing staves, comprising a frame, a main driving-shaft, a cylindrical saw, a vertically and radially adjustable table for supporting a billet to be sawed, a carriage for carrying the billet to the saw comprising a suitable frame supporting clamping-jaws, automatically operated to clamp the billet by toggle-levers and stops and automatically operated to release the billet by said toggle-levers and a spring, means for imparting a back-and-forth movement to the carriage, a pivoted stave-support mounted within the saw and a conveyer.

15. A machine for sawing staves, comprising a frame, a main driving-shaft, a cylindrical saw, a vertically and angularly adjustable table for supporting the billet to be sawed, a carriage for carrying the billet to the saw, means for imparting a back-and-forth movement to the carriage, comprising a counter-shaft, means for driving, a worm thereon, a worm-gear upon a slidable cross-shaft meshing with said worm, a friction-disk upon the shaft with the worm, friction-disks mounted upon separate shafts upon each side of the first-mentioned disk, gear-wheels upon said shafts adapted to mesh together and an additional gear-wheel upon one of said shafts adapted to mesh with a rack-bar upon the carriage, a pivoted stave-support mounted within the saw and a conveyer.

16. A machine for sawing staves, comprising a frame, a main driving-shaft, a cylindrical saw, a vertically and angularly adjustable table for supporting the billet to be sawed, a carriage for carrying the billet to the saw, means for imparting a back-and-forth movement to the carriage comprising suitable friction-disks and gear-wheels, means for automatically reversing the movement of the carriage comprising a slidable shaft upon which one of the friction-disks is mounted also being provided with a cam

adapted to engage a rigid cam upon the main frame, a spring upon the shaft for returning it to its normal position and an upwardly-extending arm upon the shaft adapted to be engaged by stops upon the carriage, a pivoted stave-support mounted within the saw and a conveyer.

17. A machine for sawing staves, comprising a frame, a main driving-shaft, a cylindrical saw, a vertically and angularly adjustable table for supporting a billet to be sawed, a carriage for carrying the billet to the saw,

means for imparting a back-and-forth movement to the carriage, means for automatically reversing the movement of the carriage, means for regulating the speed of the carriage, a pivoted stave-support mounted within the saw, and a conveyer. 15

Signed by me at Chicago, Cook county, Illinois, this 24th day of May, 1905.

ELLSWORTH E. FLORA.
